UNITED STATES PATENT OFFICE

145,734

DESIGN FOR A COMBINATION DESK UNIT

Laurence W. Kendrick, Wellesley, Mass., assignor to The Carter's Ink Company, Cambridge,
Mass., a corporation of Massachusetts

Application April 10, 1946, Serial No. 128,448

Term of patent 7 years

(Cl. D74—1)

To all whom it may concern:

Be it known that I, Laurence W. Kendrick, a citizen of the United States and resident of Wellesley, in the county of Norfolk, State of Massachusetts, have invented a new, original, and ornamental Design for a Combination Desk Unit, of which the following is a specification, reference being had to the accompanying drawing, forming part thereof.

Fig. 1 is a front perspective view of a combination desk unit showing my new design; and
Fig. 2 is a side elevation thereof.

I claim:

The ornamental design for a combination desk unit, substantially as shown.

LAURENCE W. KENDRICK.
